CLAIM

The ornamental design for a retainer for golf clubs, as shown and described.

DESCRIPTION

FIG. 1 is a top, front and left side perspective view of a retainer for golf clubs showing my new design;

FIG. 2 is a top plan view thereof;

FIG. 3 is a rear and left side perspective view thereof;

FIG. 4 is a rear and right side perspective view thereof;

FIG. 5 is a rear elevational view thereof;

FIG. 6 is a bottom plan view thereof;

FIG. 7 is a front elevational view thereof; and

FIG. 8 is a right side elevational view thereof.

The protective tubes for golf club handles are broken away in FIGS. 1, 3 through 5, 7 and 8 for convenience of illustration.

FIG 2

FIG. 1

FIG. 4

FIG. 3

FIG. 5

FIG. 6

FIG. 7

FIG. 8
